UNITED STATES PATENT OFFICE

163,701

MOTORCYCLE

Conrad La Rochelle, White Plains, N. Y.

Application May 7, 1948, Serial No. 146,209

Term of patent 14 years

(Cl. D90—16)

To all whom it may concern:

Be it known that I, Conrad La Rochelle, a citizen of the United States, residing at 11 Lafayette Street, White Plains, in the county of Westchester, New York, have invented a new, original, and ornamental Design for a Motorcycle, of which the following is a specification, reference being had to the accompanying drawing, constituting a part hereof.

Fig. 1 is a side elevational view of a motorcycle, showing my new design;

Fig. 2 is a top plan view thereof;

Fig. 3 is a rear elevational view thereof; and

Fig. 4 is a perspective view of one of the carrier units with the cover lifted and detached from the motorcycle.

The dominant features of my new design reside in the portions shown in solid lines in the drawing.

I claim:

The ornamental design for a motorcycle, substantially as shown and described.

CONRAD LA ROCHELLE.
